UNITED STATES PATENT OFFICE.

CAROLINE R. FRANTZ, OF WILMINGTON, DELAWARE, ASSIGNOR TO ABRAM E. FRANTZ,
OF WILMINGTON, DELAWARE.

METHOD OF ATTACHING WALL-PAPER.

1,026,793.

Specification of Letters Patent.

Patented May 21, 1912.

Application filed September 13, 1911. Serial No. 649,079.

To all whom it may concern:

Be it known that I, CAROLINE R. FRANTZ, a citizen of the United States, residing at Wilmington, county of Newcastle, State of 5 Delaware, have invented certain new and useful Improvements in Methods of Attaching Wall-Paper, of which the following is a specification.

This invention relates to securing in place 10 on a wall, ceiling or other surface, wall-paper which has a water-proofed backing.

My invention was designed primarily for use in connection with comparatively stiff 15 paper having an enameled face and a water-proofed back, such as disclosed in my Patent No. 935,903, granted October 9, 1909, but it is, of course, not limited to that use.

The novel features of the invention will 20 be apparent from the following description taken in connection with the drawings.

In the drawings, Figure 1 is a sectional view of a portion of a wall having wall-paper secured thereto in accordance with my method; Fig. 2 is a view of the back portion 25 of a piece of wall-paper, of the construction shown in my prior patent, and Fig. 3 is a face view showing the enameled surface of the wall-paper.

In Fig. 1 of the drawings, 1 represents a 30 portion of a wall or other surface, 2 represents the wall-paper, and 3 represents the mineral cement used by me in securing the wall-paper in place.

In carrying out my invention, I make use 35 of a wall-paper which has a water-proofed backing and it will, of course, be understood that the paper may be rendered water-proof by painting, varnishing, or soaking in oil. The cement which I use, I term "mineral cement" and I may make it as described in my prior patent, of a composition of spirit or water-proof varnish and mineral matter in finely powdered condition, such as lime, gypsum or like material 40 the mineral matter being used in such proportion to the varnish as to secure an opaque coating. This cement is to be mixed in such a way as to be thick, containing very little moisture. It is to be applied either to the 45 water-proofed backing of the paper, to the surface of the wall to which the paper is secured, or to both, and while it is in a plastic condition, the wall-paper is pressed uniformly in place on the surface. In this 50 process the paper itself is not soaked or

moistened, as has been done in the process heretofore in use in applying wall-paper. The ordinary process of applying wall-paper involves moistening the paper and the use of a paste or cement which is in a 60 very wet condition, the moisture contained in the paste subsequently evaporating through the pores of the paper. In my process the mineral cement contains very little moisture and that moisture cannot 65 penetrate the paper or escape through it since the backing of the paper is water-proofed.

As above indicated, I prefer to use, in carrying out my process, a paper such as 70 described in my Patent No. 935,903, in which a coating of fine mineral matter is applied to the water-proofed backing so as to form a rough surface in the shape of ridges, 4, as indicated in Fig. 2. This mineral matter on the back of the paper is hardened or dried and then the paper is used in connection with the layer of mineral cement, 3, in plastic condition to secure it on the wall. I find that the roughened 80 surface of mineral matter on the back of the paper assists materially in holding it in place, while the plastic cement is setting or hardening, but I also find that this is not necessary in order to produce good results. 85

Having thus described my invention, what I claim is:—

1. The method of securing in place wall-paper having a water-proofed backing consisting in placing a coating or layer of 90 mineral cement mixed with only sufficient water to make it plastic between said backing and the surface to which it is to be secured and pressing said paper uniformly in place, while said cement is in plastic condition.

2. The method of securing in place on a surface, wall-paper in a dry condition, which consists in providing said paper with a water-proofed backing, placing a layer 100 of mineral cement mixed with only sufficient water to bring it into plastic condition between said backing and surface and pressing said paper uniformly in place against said cement.

3. The method of securing in place on a surface, wall-paper in a dry condition, which consists in providing said paper with a water-proofed backing, placing a layer of mineral cement composed of water-proofing 110

material and finely powdered material having the characteristics of gypsum and only sufficient water to bring it into plastic condition between said backing and surface and 5 pressing said paper uniformly in place.

4. The method of securing in place on a surface, wall-paper having an enameled outer surface and a water-proofed backing having thereon a roughened surface of 10 finely powdered mineral matter which consists in placing a layer of mineral cement

mixed with only sufficient water to make it plastic between the back of said paper and the surface to which it is to be secured and pressing said paper uniformly in place. 15

In testimony whereof I affix my signature in presence of two witnesses.

CAROLINE R. FRANTZ.
